UNITED STATES PATENT OFFICE.

ALFRED J. STECKER, OF DETROIT, MICHIGAN, ASSIGNOR TO EUREKA VIBRATOR CO.,
OF DETROIT, MICHIGAN, A CORPORATION OF MICHIGAN.

VIBRATOR.

942,596.

Specification of Letters Patent.

Patented Dec. 7, 1909.

Application filed April 25, 1908. Serial No. 429,134.

To all whom it may concern:

Be it known that I, ALFRED J. STECKER, a citizen of the United States, residing at Detroit, in the county of Wayne and State of Michigan, have invented certain new and useful Improvements in Vibrators; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to a vibrator for massaging purposes, and consists in the construction and arrangement of parts herein-after more fully set forth and pointed out particularly in the claims.

20 The object of the invention is to provide simple and efficient means for causing a vibration or gyration of the applicator, wherein the arrangement is such as to permit the vibratory movement to be regulated 25 at will, so as to afford by a simple adjustment, any degree of vibration desired. It has been found that in vibrators of this class, a variation of the vibratory movement is absolutely essential so as to enable the degree 30 of vibration to be regulated accordingly as the point of application is changed or the conditions vary, it being essential that the means of adjustment be convenient and easily operable that the desired variations 35 in the vibratory movement may be readily made.

The above object is attained in the manner desired by the mechanism illustrated in the accompanying drawings, in which:—

40 Figure 1 is an elevation of a vibrator embodying my invention. Fig. 2 is an enlarged detail in longitudinal section through the front end of the case, and through the parts which impart vibratory movement to 45 the applicator, showing the means for adjusting said parts to regulate the vibration. Fig. 3 is a similar view, showing the position of parts when adjusted to afford the maximum vibration. Fig. 4 is a fragmentary view in elevation with parts in section, showing the construction of the ball and socket joint at the end of the case, the means for preventing the rotation of the ball while allowing said ball to tilt or rock in its confining bearings.

Referring to the characters of reference, 1 designates a suitable case or supporting frame mounted on a handle 2. Within the case or frame is a suitable electric motor indicated at 3 in Fig. 3, from which extends 60 the motor shaft 4. Secured to the end of the shaft and rotatable therewith is a socket member 5 having a socket 6 therein which is inclined with respect to the axis of said member, the outer end of said socket being 65 eccentric to said axis, and the inner end concentric thereto. Within the outer end of the case is a spherical member or ball 7 which is seated in and confined between two hemispherical shells 8 and 9 respectively 70 which embrace said ball, the inner shell 9 being seated in the opening in the end of the case, and the outer shell 8 being engaged by the gland 10 which screws onto the end of said case to confine and retain said parts. 75 By adjusting said gland, any desired tension may be placed upon the members forming the ball and socket joint, and by means of the set screw 11 shown in Fig. 1, when adjusted, said gland may be locked. 80

Passing centrally through the ball and through the hemispherical shells which embrace it and which are provided with openings for that purpose, is a longitudinally reciprocatory rod 12 which is externally 85 threaded, as shown at 13, and is provided at its extreme outer end with a threaded socket member 14 into which is screwed the stem 15 of the applicator 16, which is herein shown in the form of a rubber cup, but the form and character of which may be varied at pleasure. The rod 12 passes freely through the ball 7 and upon its inner end is provided with a rotary ball 17 which is adapted 90 to lie in the socket 6 of the member or coupling 5 on the end of the motor shaft 4. Secured to the rod 12 near its inner end is a collar 18, and confined between said collar and the ball 7 is a compressible spring 19. Screwed onto the threaded portion 13 of the rod 12 is an adjusting disk 20 by a rotation 100 of which the rod 12 may be adjusted longitudinally, causing the ball 17 on the inner end thereof to slide within the socket 6 of the rotary member 5. To limit the longitudinal movement of the rod 12 through the ball 7, said rod is provided with a key-seat 21 therein (see Fig. 2), into which extends the inner end of the pin 22 which is fixed in the ball 7, and whose outer end lies in a slot 110

23 formed in the end of the case, as clearly shown in Fig. 4. The presence of said pin 22 in the channel or key-seat in the rod 12, limits the longitudinal movement of said 5 rod, while the outer end of said pin lying in the slot in the end of the case, prevents a rotary movement of said rod and of the ball 7, the size of said slot 23 however, being such as to permit of the tilting or rocking 10 movement of said ball.

When the parts are in the position shown in Fig. 2, a rotation of the shaft 4 and coupling member 5, will impart no vibratory movement to the applicator 16, because of 15 the fact that the axis of the rod 12 which imparts movement to said applicator is in alinement with the axis of the shaft 4. By turning the adjusting disk 20, however, so as to screw the rod 12 through the ball 7 20 against the action of the spring 19, the ball 17 on the inner end of said rod will be drawn outwardly in the inclined slot 16 so as to cause the longitudinal axis of the actuating rod 12 to stand at an angle to the axis of the 25 shaft 4, as clearly shown in Fig. 3, thereby imparting, as the shaft 4 revolves, a gyroscopic movement to the applicator 16 attached to the outer end of said rod 12. By turning the disk 20 in the opposite direction, the 30 force of the spring 19 will draw the rod inwardly, causing the ball 17 on the inner end thereof to enter the socket in the rotary member 5, and as said ball gradually approaches the axis of rotation of shaft 4, the 35 degree of vibration applied to the applicator 16 will be correspondingly reduced. By this simple arrangement, the gyroscopic movement imparted to the applicator may be regulated so as to render the vibration as light or as 40 severe as desired, the arrangement being such as to enable the degree of vibration to be readily varied while the instrument is in operation. It will be understood that when the rod 12 is out of alinement with the axis 45 of the shaft 4, a rotation of said shaft will cause the inner end of said rod to describe a circle about the axis of said shaft to accommodate which movement the ball 7 will rock or tilt in its confining shells.

50 Having thus fully set forth my invention, what I claim as new and desire to secure by Letters Patent, is:—

1. In a vibrator, the combination of a supporting frame, a rotary member journaled 55 therein, an applicator, means for transmitting movement to the applicator comprising a spherical member jointedly seated in the frame, a rod passing through said member and movable longitudinally therein, one end 60 of said rod having a sliding engagement with said rotary member, and means carried by said rod exterior of the frame for adjusting it longitudinally through the spherical member to adjust the sliding engagement 65 of said rod with said rotary member.

2. In a vibrator, the combination of a supporting frame, a rotary member journaled therein, a spherical member jointedly seated in the frame and fixed with respect to said rotary member, an applicator, means for 70 transmitting movement to the applicator comprising a longitudinally movable rod fast to the applicator at one end, and having sliding engagement at the other end with said rotary member, said rod being movable 75 through the spherical member, and means for moving said rod longitudinally.

3. In a vibrator, the combination of a supporting frame, a rotary member therein provided with a socket disposed at an angle 80 to the axis of said member, a ball jointedly seated in said frame, an applicator, means for imparting movement to the applicator, said means comprising a longitudinally movable rod connected with the applicator 85 at one end, and at the other end engaging in the socket of said rotary member, said rod passing through and movable longitudinally in said ball, and means for adjusting the rod longitudinally to vary its engagement in the 90 socket of the rotary member.

4. In a vibrator, the combination of a supporting frame, a rotary member journaled therein, an applicator, a longitudinally movable rod connected with said applicator 95 at one end, and having a sliding engagement at the other end with said rotary member, a ball jointedly seated in the frame through which said rod is longitudinally movable, and an adjusting disk threaded on said rod 100 and engaging a fixed part to effect a longitudinal movement thereof.

5. In a vibrator, the combination of a supporting frame, a rotary member journaled therein having an inclined socket, a ball 105 jointedly seated in the frame, a rod passing through said ball, an applicator connected with the outer end of said rod, the inner end of said rod engaging in the socket of the rotary member, a spring connected to said rod 110 at one end and at the other end engaging a fixed part for moving said rod in one direction, and means for moving the rod longitudinally against the action of said spring.

6. In a vibrator, the combination of a supporting frame, a rotary member journaled therein, an applicator, operating means extending between the applicator and rotary member and having sliding connection with the latter, said means comprising a longitudinally movable rod pivotally mounted in the frame, a spring upon said rod connected thereto at one end and at the other end engaging a fixed part, and means for adjusting the rod longitudinally against the action 120 of said spring to vary its sliding engagement with said rotary member.

7. In a vibrator, the combination of a frame, a rotary member journaled in said frame, an applicator, operating means con- 130

nected with the applicator, said operating means extending between the applicator and rotary member, said means comprising a rod having a sliding engagement with the rotary member and movable longitudinally, said rod being pivotally mounted in the frame, a disk threaded on said rod engaging a fixed part for adjusting it longitudinally, and a spring to return said rod.

8. In a vibrator, the combination of a supporting frame, a rotary member journaled therein, an applicator, a longitudinally movable rod connected with the applicator and having sliding engagement with said rotary member, a ball jointedly seated in the frame through which said rod is longitudinally movable, said rod having a key-seat therein, a pin passing through the ball and extending into the seat, and means for adjusting the rod longitudinally.

9. In a vibrator, the combination of a supporting frame, a rotary member journaled therein, an applicator, a longitudinally movable rod extending between the applicator and said rotary member and having sliding engagement with the latter, a ball jointedly mounted in the frame, said rod passing through said ball and movable longitudinally therethrough, a pin seated in said ball, a key-seat in said rod in which the inner end of said pin engages, the frame having a notch that receives the outer end of said pin, a spring upon the inner end of the rod confined between its inner end and said ball, and an adjusting disk threaded on the outer end of said rod.

10. In a vibrator, the combination of a supporting frame, a rotary member journaled therein, an applicator, a longitudinally movable rod connected with said applicator at one end, and having a sliding engagement at the other end with said rotary member, a ball jointedly seated in the frame through which said rod is longitudinally movable, and means for adjusting the rod longitudinally,

and means for preventing a rotation of the rod and ball.

11. In a vibrator, the combination of a supporting frame, a rotary member journaled therein, an applicator, a longitudinally movable rod connected with said applicator at one end, and having a sliding engagement at the other end with said rotary member, a bearing member jointedly seated in the frame through which said rod is longitudinally movable, an adjusting disk threaded on the rod engaging said bearing member, and a spring confined between said bearing member and the inner end of said rod.

12. In a vibrator, the combination of a supporting frame, a rotary driving member therein, a bearing member pivoted on the frame fixed with respect to said rotary driving member, a rod passing through said bearing member and longitudinally movable therein, the inner end of said rod having a movable connection with said driving member, an applicator connected with the outer end of said rod, and means for moving the rod longitudinally through said bearing member to adjust its connection with said rotary driving member.

13. In a vibrator, the combination of a supporting frame, a rotary driving member therein, a ball held in a socket in the frame to have movement therein, an actuating rod mounted in the ball to slide longitudinally therethrough, one end of said rod movably engaging said rotary member, an applicator connected with the outer end of said rod, and means for moving said rod longitudinally through said ball.

In testimony whereof, I sign this specification in the presence of two witnesses.

ALFRED J. STECKER.
